STADIUM SEAT

Joseph P. Necessary, 1410 Spring, Huntington, W. Va.
Filed Mar. 22, 1963, Ser. No. 267,126
3 Claims. (Cl. 297—184)

This invention relates to a portable stadium seat which may be carried to a stadium, or to some other place or establishment equipped with fixed rough seats or benches, and attached to such seats or benches for the purpose of providing additional comfort and protection from the elements.

Thus the term "stadium seat" actually encompasses a seat which is suitable for attachment to the rough seats and benches of a stadium, or to any other fixed seats or benches, including by way of example, but not by way of limitation, such seats in parks, on boats, or in other places where a person is likely to experience unpleasant or uncomfortable exposure to the elements.

It is an object of this invention to provide such a stadium seat which is light enough to be carried easily by a person of normal strength and endurance, and can be quickly and easily assembled at the place of use in a manner to give the user a maximum degree of protection from sun, wind, rain, sleet and snow.

Other objects of the invention will be more fully understood from the following detailed description of a typical preferred form and application of the invention, throughout which description reference is made to the accompanying drawings in which—

FIGURE 1 is a perspective view of the stadium seat;

FIGURE 2 is an elevational view of the canopy and the canopy housing, the canopy being illustrated when fully withdrawn from the housing but not inserted into the coves as is described hereinafter;

FIGURE 3 is a section, with portions broken away, taken along lines 3—3 of FIGURE 1;

FIGURE 4 is a section taken along lines 4—4 of FIGURE 2;

FIGURE 5 is a plan view, looking upwardly, of the seat portion of the stadium seat;

FIGURE 6 is an end elevational view of the seat portion of the stadium seat when the same is attached to a stadium seat or bench.

Referring to FIGURE 1 it will be seen that the stadium seat comprising this invention is adopted for placement upon a rough seat or bench 10, as found in a typical stadium.

The stadium seat includes a seat member 12 which is connected by hinge members 14 to a back member 16. As will be evident, the back member 16 can be folded forwardly to a position flush to the upper surface of the seat member 12, but can only move rearwardly of the stadium seat as a whole to the position shown in the drawing, further rearward movement being prevented by folding braces 18.

Fixably mounted on each transverse edge of the back member 16 are socket members 20 which are so internally dimensioned as to snugly receive one end of a L-shaped canopy support member generally indicated at 22.

As best shown in FIGURE 1, one leg 24 of each canopy support member 22 has its free end formed to snugly fit into the socket member 20, so that the leg extends vertically upward. The other leg 26 extends generally horizontally over the seat member 12, i.e. from the back thereof toward the front thereof to a position slightly in front of the front edge of the seat member 12. Stated otherwise, each leg 26 of the respective canopy support member 22 extends in a direction parallel to the other leg 24. In the preferred embodiment shown, the canopy support member 22 is formed of two telescopically interfiting sections, one of which comprises the major portion

2

of the vertically extending leg 24 and the other of which comprises the horizontal leg 26 as well as the bend 27 in the member.

It will, of course, be understood that it is equally within the contemplation of this invention that the two interlocking sections be so formed that one of them comprises all of the vertically extending leg 24 as well as the bend 27 in the canopy support member 22, and that the other section should merely comprise a major portion of the horizontally extending leg 26. In like manner it is fully within the scope of this invention that the canopy support member 22 may be formed of three sections, i.e. two leg sections and one bend section.

In the preferred embodiment shown, the canopy support member is formed of circular tubing although it will be understood that it is within the contemplation of this invention that it can be formed with tubing of some other shape or from solid stock, although in the latter case other conventional arrangements will have to be made for the junction of the respective portions thereof.

In any event the members defining the bend 27 and the respective legs 24 and 26 of the canopy support member 22 have a cove 30 mounted on the rearwardly facing end and the upwardly facing surface thereof as best shown in FIGURE 4. Each cove has its opening 32 so arranged as to face the other cove, or, stated otherwise, to face in a direction transverse of the stadium seat as a whole.

An elongated canopy housing 24 is positioned to extend along the rear edge of the seat member 12, to which it is affixed by brackets 36. As best shown in FIGURE 4, the canopy housing contains a roller 38 upon which a cloth canopy 39 is wound. The roller 38 is spring biased with a slip-ratchet arrangement of the conventional type as used on conventional window shade rollers. As such spring biased slip-ratchet winding mechanisms are widely known in the art, and do not in themselves form any part of this invention, no detailed description of such mechanisms will be presented here.

As is best shown in FIGURE 4, the canopy housing has a slit 40 extending from a point adjacent one end thereof to a point adjacent to the other end, said slit being dimensioned and arranged to allow for ingress and egress of the canopy 39 which will now be described.

As best shown in FIGURE 2, the canopy consists of a main panel portion 42, which when in use, comprises the back and top portions of the canopy, and also includes side panel portions 44 which are shaped to conform with the shape defined by that portion of a canopy support member 22 which overlies the seat member 12. When the canopy as a whole is folded in the manner shown in FIGURE 2, i.e. with the side panels folded to overlie the main panel 42, the transverse edges of the folded canopy present a bead 46 which, as best shown in FIGURE 3, is so dimensioned that it can fit within the cove 30 but will not pass through the opening 32 thereof.

One end of the canopy is permanently affixed to the roller 38. The free end of the canopy is affixed to an end member 48 which extends from a point near one edge of the canopy, but short of the bead 46 at that edge, to a point near the second edge of the canopy, but short of the bead 46 at that edge. The end member 48 is at least partially hollow and serves to support pins 50 located with each end thereof, such pins resiliently urged to extend outwardly from the ends of the end member 48 by spring means 51.

In this preferred embodiment, the pins extend to, or are otherwise connected with, finger clasps 52 located at the midpoint of the end member 48 and are so arranged that pressing the same together with finger pressure will serve to cause the pins 50 to retract to a position substantially flush with the ends of the end member.

When the stadium seat is not in use, the canopy is placed in the folded condition illustrated in FIGURE 2 and then rolled up on the roller 38 within the housing 34, and the back member 16 is folded flush with the seat member 12.

The respective portions of each canopy support member 22 are disengaged one from the other and each leg 24 is withdrawn from its socket member 20. As shown in FIGURE 5, as a matter of convenience these elements may be secured in suitably shaped recesses 54 formed in the underside of the seat member 12.

When the stadium seat is to be used, the back member is raised to the operative position shown in FIGURE 1 and the canopy support member is assembled and installed as has been described. A small portion of the canopy is then withdrawn from the housing 34 and the beads thereof 46 are introduced into the cove 30 which, as will now be understood, is only provided in that portion of the legs 24 which are not inserted with the sockets 20. The remainder of the canopy is then withdrawn from the canopy housing in a manner wherein the bead is continually fed into the cove and thus the main panel 42 of the canopy forms a back and a cover for the stadium seat. When the canopy is fully withdrawn, the end member 48 is located substantially on line with the free ends of the legs 26. The finger clasps 52 are operated to withdraw the pins 50 while the end member is positioned so that the pins are aligned with pin holes 56, which, as can best be seen on FIGURE 1, are but a short distance from the free ends of the legs 26. Release of finger pressure on the finger clasps 52 then allows the pins 50 to project into the pin holes 56 so that the end of the canopy is firmly affixed in position.

At that point the side panels 44 are brought around the legs 26 and are secured to the canopy support members and to the edges of the seat member 12. In the preferred embodiment shown, this attachment is obtained by conventional snap fasteners 58 which are so dimensioned and positioned as to detachably engage suitably positioned studs located on the outwardly facing (of the stadium seat as a whole) surfaces of the seat and the canopy support member. Such snaps are well known in the art and are not claimed to be a part of this invention.

As shown in FIGURES 5 and 6 the underside of the seat member 12 is provided at the back edge with two fixed brackets 62 for engaging the rough seat or bench 10 and is provided at the front with one adjustable bracket 64 which may be drawn snugly against the underside of the rough bench by suitable manipulation of wing nut 66 on bolt 68, the arrangement being that the bolt passes through a portion of the adjustable bracket and that tightening the wing nut will draw the bracket up tight against the rough bench and will therefore securely fix the stadium seat in position so that it will not slide about when the occupants of the stadium seat shift their positions.

It should be understood that while the canopy described hereinabove has been referred to as being made of cloth, it is within the contemplation of this invention that such cloth is not necessarily a woven material, but rather may, and in the preferred embodiment is, formed of a homogeneous material such as plastic film.

Having described only a typical form and embodiment of the invention, I do not wish to be limited or restricted to specific details herein set forth but wish to reserve to myself any variations or modifications that may appear to those skilled in the art and falling within the scope of the following claims.

I claim:

1. A stadium seat comprising a seat member, a back member, hinge means engaging said seat member to said

back member to allow the latter to fold flush with the former when the stadium seat is not in use, a pair of L-shaped canopy support members, means for fixing one of said canopy support members to each end of said back member in a position wherein a first leg of each canopy support member extends vertically, and a second leg thereof extends horizontally over the seat member, a cloth canopy member, a canopy storage roller mounted along the rear edge of the seat member, said cloth canopy member having end portions affixed to said roller, means on said canopy support members for receiving and retaining transverse edges of the cloth canopy member, whereby the cloth canopy member can be drawn from the canopy storage roller to a position wherein it extends behind and over a person occupying the stadium seat, and is secured in that position by its engagement with the canopy support members, said cloth canopy member further including, as integral parts thereof, side panel portions which extend from the said second legs of the canopy support member to the seat on each side of the stadium seat, and means to detachably secure the side panels in that position.

2. A stadium seat comprising a seat member, a back member, hinge means engaging said seat member to said back member to allow the latter to fold flush with the former when the stadium seat is not in use, a pair of L-shaped canopy support members, means for fixing one of said canopy support members to each end of said back member in a position wherein a first leg of each canopy support member extends vertically, and a second leg thereof extends horizontally over the seat member, a cloth canopy member, a canopy storage roller mounted along the rear edge of the seat member, said cloth canopy member having end portions affixed to said roller, means on said canopy support members for receiving and retaining transverse edges of the cloth canopy member, whereby the cloth canopy member can be drawn from the canopy storage roller to a position wherein it extends behind and over a person occupying the stadium seat, and is secured in that position by its engagement with the canopy support members, said cloth canopy member further including, as integral parts thereof, side panel portions which extend from the said second legs of the canopy support member to the seat on each side of the stadium seat, and means to detachably secure the side panels in that position.

3. The structure defined in claim 2 and further including a rigid canopy end member affixed to a second end of the canopy, means for securing said canopy end member to the second legs of the canopy support member adjacent the free ends thereof.
